(57) **CLAIM**

We claim the ornamental design for a driver tool, as shown and described.

DESCRIPTION

FIG. 1 is a perspective view of the claimed design according to one embodiment.

FIG. 2 is a left side view thereof.

FIG. 3 is a right side view thereof.

FIG. 4 is a rear view thereof.

FIG. 5 is a front view thereof.

FIG. 6 is top view thereof.

FIG. 7 is a bottom view thereof.

FIG. 8 is a perspective view of the claimed design according to another embodiment.

FIG. 9 is a left side view thereof.

FIG. 10 is a right side view thereof.

FIG. 11 is a rear view thereof.

FIG. 12 is a front view thereof.

FIG. 13 is top view thereof; and,

FIG. 14 is a bottom view thereof.

The broken lines in the drawings are for illustrative purposes only and form no part of the claimed design.
